UNITED STATES PATENT OFFICE.

ROBERT CAMERON COLWELL, OF MORGANTOWN, WEST VIRGINIA.

MULTIPLE CONNECTER.

Application filed December 11, 1924. Serial No. 755,264.

This invention relates to multiple connectors designed for connecting a plurality of electric wires to a battery terminal or the like.

5 An important object of the invention is to provide a device of this character which will be adjustable, and wherein one or more wires may be connected to the device at the will of the operator.

10 A still further object of the invention is the provision of a connector which will grip the wires connected therewith in a manner to insure against displacement of the wires.

15 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within 20 the scope of what is claimed, without departing from the spirit of the invention.

Referring to the drawing:

25 Figure 1 is a side elevational view of a multiple connector constructed in accordance with the invention.

Figure 2 is an elevational view of the connector, parts thereof being shown in section.

30 Figure 3 is an end elevational view thereof.

Referring to the drawing in detail, the device includes a pair of spring pressed jaws 5 which are adapted to grip a battery terminal or the like to secure the device thereto.

35 The spring jaws include body portions 6 which carry spring fingers 7 on opposite sides thereof and cooperate with the spring arms 8 that are provided with suitable slots to permit the members 8 to be moved downwardly over the fingers 7 in such a way that the outward pressures of the arms 8 will tend to hold the wire terminals 9 in position.

40 The arms 8 have outwardly extended portions 10 that are formed with suitable openings to accommodate the securing screws 11 that pass into the body portions of the multiple connectors, there being two forms of connectors illustrated by Figure 2 of the drawing. The connector illustrated by the reference character 12 includes an elongated body portion threaded externally to accommodate the nut 13 which nut acts to 45 secure the connectors 14 in position.

An elongated opening 15 is formed in the body portion 12 and accommodates the cord terminals 16 that are positioned in the body portion. The connectors 14 are formed of sheet metal and are relatively wide, the sheet metal being bent to provide opposed members 17 so constructed that they normally exert a pressure away from each other to the end that the cord terminals supported 60 between adjacent connectors 14 will be closely engaged by the members thereof.

65 As shown by Figure 2, a pair of cord terminals are secured, but it is to be understood that by removing the nut 13 and placing another connector thereon, still another cord terminal could be held on the body portion.

70 The connector as illustrated by the lower portion of Figure 2, includes a plurality of removable members 18, each of which being 75 provided with a socket 19 threaded to receive the threaded extensions 20 of the adjacent connector. Each of the members 18 is formed with a skirt 21 adapted to engage the cord terminal supported between adjacent removable members 18 to clamp the 80 cord terminal.

85 A screw indicated at 22 passes into the removable member disposed adjacent to the outwardly extended portion 23 of the arm 85 employed for supporting the removable connector.

90 From the foregoing it will be obvious that due to this construction a plurality of these members 18 may be connected and secured together in the manner as described.

I claim: —

95 A multiple connector embodying a plurality of removably connected members, each member having a socket at one end and having a threaded opening communicating with the socket, each member having an extension at its opposite end of a diameter to fit within the socket of the adjacent member, said extension having a reduced threaded 100 portion fitted in the threaded opening, and the extension having an opening to permit a wire to pass therethrough, and one edge of one removable member adapted to engage the wire of the adjacent movable member to 105 secure the wire in position.

In testimony that I claim the foregoing as my own, I have hereto affixed my signature.

ROBERT CAMERON COLWELL.
